UNITED STATES PATENT OFFICE.

HANS HEYNAU, OF DOTZHEIM, NEAR WIESBADEN, GERMANY.

THOROUGHFARE TAP-HOLDER.

No. 880,529.

Specification of Letters Patent.

Patented March 3, 1908.

Application filed April 10, 1907. Serial No. 367,333.

To all whom it may concern:

Be it known that I, HANS HEYNAU, engineer, a subject of the King of Saxony, residing at Dotzheim, near Wiesbaden, in the 5 Kingdom of Prussia and German Empire, have invented new and useful Improvements in Thoroughfare Tap-Holders, of which the following is a specification.

My invention relates to an improved tap 10 holder, designed more particularly for use in tapping thoroughfare holes in wholesale work.

The invention is illustrated in the accompanying drawing, in which

Figure 1 is an elevation, partly in section, 15 of the new holder. Fig. 2 is an elevation, the holder being viewed at right angles to Fig. 1. Fig. 3 is an underside view of the holder. Fig. 4 is an end view. Fig. 5 is a section of a socket to be hereinafter referred to. 20 Fig. 6 is a cross-section through the socket on the line A—B of Fig. 5, and Fig. 7 shows a small steel wire spring.

The top part of the holder *a* is conical and may be fitted into an ordinary drilling 25 machine. The lower portion is recessed and receives a sliding head *b*, caused to partake of the rotary motion of the holder by means of a feather *c*, and having an internal square adapted to receive the tap.

When the tap has cut through the hole, the 30 descending head *b* is forced down upon the work and is consequently pressed back into the recess in the holder. Into the bottom of the recess there is screwed a pin *d*, which 35 when the head *b* has been pushed back against the recess bottom, knocks the tap out of the

holder *a*, so that it drops upon the table of the machine. On the holder *a* being run up, the head *b* is returned to its initial position by a spring *f*, coiled round the pin *d*, the one end 40 bearing against the bottom of the recess and the other end against a disk *g* resting upon the square in the head *b*. The tap can now be reinserted in the head.

In order to adapt the holder for taps of 45 different sizes, sockets such as shown in Figs. 4 and 5 may be inserted in the head *b*. These sockets have an external square 50 adapted to fit the head *b* and an internal square to receive the tap in use. The entire 55 holder is made of magnet steel and strongly magnetized, so that the taps and sockets may be effectively prevented from dropping out. If desired, small springs *s* made of steel wire may be inserted in the head and socket as shown in Figs. 1, 5 and 6 to serve the same purpose as magnetization.

What I do claim as my invention and desire to secure by Letters Patent, is:—

A tap holder comprising a shank having a 60 recess, a pin projecting thereinto and a spring actuated tap receiving head having a bore slidably in the recess and splined to the shank.

In testimony whereof I have signed my 65 name to this specification in the presence of two subscribing witnesses.

HANS HEYNAU.
